UNITED STATES PATENT OFFICE.

ELIZABETH LYNCH, OF MINNEAPOLIS, MINNESOTA.

SCREEN.

1,109,437.

Specification of Letters Patent.

Patented Sept. 1, 1914.

Application filed September 19, 1913. Serial No. 790,730.

To all whom it may concern:

Be it known that I, ELIZABETH LYNCH, a citizen of the United States, residing at Minneapolis, in the county of Hennepin and State of Minnesota, have invented new and useful Improvements in Screens, of which the following is a specification.

The invention relates to an improvement in screens and particularly to a screen constructed with a simple and effective form of fly escape.

The main object of the present invention is the provision of a screen embodying practically the usual frame and screen cloth, the frame being peculiarly constructed at the upper end to form an effective fly escape in the screen cloth.

The invention in its preferred form of details will be described in the following specification, reference being had particularly to the accompanying drawings, in which:

Figure 1 is an elevation. Fig. 2 is a vertical central section of the same. Fig. 3 is a transverse section on the line 3—3 of Fig. 1.

Referring particularly to the accompanying drawings, my improved screen comprises a frame including side and end bars 1 and 2, all of which, with the exception of the upper end bar 2, are of the usual construction and form no material part of the present invention. The upper end bar, which has a width corresponding to the similar dimension of the lower end bar at its relatively inner surface, is projected in alignment with the surface of the adjacent side bars, as at 3, and from this portion 3 inclines inwardly to present an inclined surface 4 which extends inwardly and downwardly with relation to the relatively outer or screen cloth receiving surface of the side bars. The relative lower edge 5 of the upper cross bar of the frame is of appreciable width, being approximately one half the thickness of the side bars.

The screen cloth 6 is secured to the outer surface of the side bars and lower end bar in the usual manner, the usual sealing strips 7 being applied and preferably extended across the inner surface of the upper end bar 2 and so complete the configuration. In line with the lower edge of the upper frame bar the screen cloth, which has been reduced in width at this point to correspond to the distance between the inner surface of the side bars, is bent laterally to form a ledge

8, and the outer edge of the laterally projected portion is secured beneath the lower edge 5 of the upper frame bar and preferably secured thereto by the usual sealing strip 9. At the juncture of the ledge 8 with the main length of the screen cloth there are formed openings 10 providing the fly escape openings.

The function of the screen in use will be readily apparent from the above description, taken in connection with the drawings, it being evident that the inclined surface provides a space for the ledge of the screen cloth and for the formation of proper escape openings in said cloth. Of course, it is to be understood that I contemplate constructing the screen of any size or of any material, varying the proportion of the details of the improvement in accordance with the size of the screen used.

What is claimed is:

1. A screen including side and end frame bars, the upper frame bar having its inner or lower edge of less width than its upper edge throughout the full length of said bar between the side bars and presenting an inclined inner surface leading from the lower edge toward the upper edge, the upper edge of the screen cloth being secured beneath the lower edge of the upper frame bar and presenting a lateral projection at its upper edge throughout the full length of the screen cloth intermediate the side bars.

2. A screen including side and end frame bars, the upper frame bar having its inner or lower edge of less width than its upper edge throughout the full length of said bar between the side bars and presenting an inclined inner surface leading from the lower edge toward the upper edge, the upper edge of the screen cloth being secured beneath the lower edge of the upper frame bar and presenting a lateral projection at its upper edge throughout the full length of the screen cloth intermediate the side bars, said screen cloth at the juncture of the lateral projection and main length of said cloth being formed with openings.

In testimony whereof I affix my signature in presence of two witnesses.

ELIZABETH LYNCH.
